CIRCUIT BREAKER WITH LEVER TYPE
CURRENT CONNECTION

Chester D. Ainsworth, Wollaston, and Gustav E. Jansson, North Quincy, Mass., assignors to Allis-Chalmers Manufacturing Company, Milwaukee, Wis., a corporation of Delaware

Application December 7, 1948, Serial No. 63,932

9 Claims. (Cl. 200—82)

1

This invention relates in general to improvements in electric circuit breakers, and more particularly to means for conducting currents of relatively large intensity from one stationary terminal of the breaker to the movable contact of the breaker associated therewith.

Heretofore, the performance of flexible conductors for electrically interconnecting a stationary terminal and a relatively movable solid conductor has often proven unsatisfactory, and their use for this purpose tended to become more objectionable as the speed and frequency of contact actuation increased. Flexible conductors have a limited flexural life due to fatigue or oxidation, thus requiring replacements at regular intervals of time.

It is, therefore, desirable to provide circuit breakers that are called upon to operate frequently with solid interconnecting conductors rather than flexible interconnecting conductors. An arrangement of this type comprising a solid interconnecting conductor calls for spring means for establishing the requisite contact pressure between this interconnecting conductor and contact surfaces associated therewith. In high speed circuit breakers of the gas blast type the light weight movable contact is generally operated by a pneumatic motor having a piston which is moved to the contact open position thereof by gas under pressure, and which is returned to the contact closed position upon removal of the gas pressure therefrom by spring action. The spring means used to establish the requisite contact pressure between the solid interconnecting conductor and the contact surfaces associated therewith may serve a dual function as claimed in this application by being adapted in addition to move the piston of the pneumatic motor and the movable contact associated therewith from contact open position to contact closed position.

It is therefore one of the objects of the present invention to provide a new and improved circuit breaker of the fluid blast type in which a rigid conductor is used to interconnect a movable conductor and a stationary terminal associated therewith.

Another object of the present invention is to provide a new and improved circuit breaker in which an element is used both to interconnect a movable contact and a stationary terminal element associated therewith and to transmit the requisite actuating force to the movable contact for movement thereof in one direction.

A further object of the present invention is to provide a new and improved circuit breaker in

2

which a spring means requiring a minimum amount of space is used to reset a pair of cooperating contacts and wherein the spring means has a smaller stroke than the movable contact.

5 A still further object of this invention is to provide a new and improved circuit breaker in which a dual purpose spring means actuates a movable contact and establishes contact pressure between a rigid element and the movable contact and terminal element associated therewith. Objects and advantages other than those above set forth will be apparent from the following description when read in connection with the accompanying drawing in which:

10 15 Fig. 1 is a view in axial cross section, of an interrupting chamber of a gas blast circuit breaker involving the present invention; and

Fig. 2 is a top view of the solid interconnecting conductor and the guiding surfaces associated therewith in the embodiment illustrated in Fig. 1.

20 Referring more particularly to the drawing by characters of reference, Fig. 1 illustrates an interrupting head 1 which comprises a flange or supporting base member 2 which is clamped by means of cap screws 3 on a cap (not shown) connecting the flange to a source of arc extinguishing fluid under pressure. Base member 2 supports a tubular insulator 4 of ceramic or other suitable insulating material of which porcelain is an example. A force is applied to a continuous clamping ring 5 by a series of screws 6 secured to base member 2 and a component of this force is transmitted through a split ring 7 onto the porcelain insulator 4 in a direction substantially perpendicular to a surface 8 of porcelain insulator 4 to secure the porcelain insulator thereto. This clamping structure minimizes bending moments and shear stresses in the porcelain.

25 30 35 40 45 50 55 A conductive annular member 9 made in two parts is mounted on and supported by insulator 4 by means of a continuous clamping ring 10, a split ring 11 and screws 12 in a manner similar to that used to secure insulator 4 to base member 2. An insulating tube 13 mounted within and axially aligned with insulator 4 is rigidly supported by base member 2 through a pressure ring 14 and surrounds a downward extending cylindrical portion 15 of conductive annular member 9 with a small clearance. Insulator tube 13 also surrounds a pair of cooperating arc ing contacts 16 and 17 and cooperates with conductive cylindrical member 9 to define an arcing chamber 18.

Contact 16 is a fixed contact shaped as a

streamlined solid of revolution and is bolted to a tubular portion 28 of base member 2 extending into insulating tube 13. Contact 16 has an arcing tip 19 of refractory conductive material in the form of a plug and is provided with a plurality of grooves 20 extending radially from substantially the tip of the plug along the outer surfaces thereof. These grooves provide passage ways for a limited flow of fluid under pressure through the arcing contacts during contact engagement thereof. The base of contact 16 comprises a plurality of fin-like appendages 21 adapted to form a plurality of air passages.

The cooperating movable contact 17 comprises an annular shaped arcing portion defining an orifice 22 and adapted to partially surround the top portion of stationary contact 16 upon engagement therewith. Contact 17 further comprises a sleeve portion 23 and forms therewith the piston of a fluid motor. Sleeve 23 is adapted to slide within guiding surfaces which, in turn, constitute downward extension portions 15 and 32 of the conductive cylindrical member 9. The upward stroke of sleeve 23 is limited by abutment of an annular projection 23a thereof against a flange 25 backed by suitable shock absorbing material. The interior of sleeve 23 is insulated by a suitable material and forms with hollow insulator 13 the arcing chamber 18.

When the arcing contacts 16 and 17 are closed they substantially close orifice 22 and essentially divide arcing chamber 18 into an inlet chamber 26 and an outlet chamber 27. The inlet chamber 26 is generally defined by insulating tube 13 and the hollow upward extending portion 28 of base member 2. The outlet chamber 27 is generally contained within sleeve 23 and extends upward to a suitable outlet 29 extending between member 9 and a concave baffle or cover 30 secured thereto. Outlet chamber 27 contains an auxiliary arcing electrode 31. This electrode, which is secured to cover 30 and in electrical contact with member 9, is usually axially aligned with sleeve 23.

A plurality of rigid interconnecting conductors 33 electrically connect the movable contact 17 to member 9, which is provided with a terminal lug 34 and therefore constitutes a stationary terminal element. Base member 2, which is electrically connected to the stationary contact 16, constitutes the second stationary terminal element and is provided with a suitable terminal lug (not shown).

Each rigid interconnecting conductor 33 is in the form of a rocking contact lever which is in permanent contact with the conductive cylindrical member 9 and sleeve 23 at all times. Sleeve 23 may be provided with a groove 35 having a concave cross section extending around the circumference thereof and forms a bearing surface 36 for engagement of one end of the interconnecting conductors 33. The conductive annular member 9, in turn, may be provided with a concave circular groove 37 having an annular supporting surface 38 adapted to hingedly support the other end of conductors 33. Levers 33 extend in radial directions from sleeve 23 and, while resting on supporting surfaces 36 and 38, make with the axis of sleeve 23 an angle which varies with the longitudinal position of the sleeve. A plurality of dual purpose spring means 39, axially aligned with a plurality of dual purpose spring means 40, provide a substantially constant pressure between flanges 25 and interconnecting

conductors 33. Thus, as piston 24 moves under the influence of air pressure, sleeve 23 moves upward in the interrupting head 1 and interconnecting conductors 33 follow the vertical movement thereof by a combined rolling and wiping action over the two contacting surfaces 36 and 38 associated therewith. Pairs of ears 41 provided on member 9 adjacent the sliding surfaces 38 guide each interconnecting conductor 33 and align these interconnecting conductors in radially extending directions from the annular groove on the outer surface of sleeve 23. Interconnecting conductors 33 may be shaped in any one of a number of ways, however, the chosen configuration must permit a freedom of movement over the supporting surfaces engaging therewith. The operable interconnecting conductors illustrated in the drawing are provided with convex end portions in engagement with the supporting surfaces, whereby movement of interconnecting conductors 33 takes place with a minimum of friction.

The helical spring means 39 act upon interconnecting conductors or levers 33 at points intermediate their ends to provide a sufficient amount of contact pressure between conductors 33 and the contact surfaces engaged therewith. However, these springs have a dual function and additionally effect resetting or reclosing of contact 17 upon the decrease of pressure in the inlet chamber 26 upstream of movable contact 17. The helical spring means 39 are disposed so as not to increase the overall dimensions of the circuit breaker. The stroke or compression of spring means 39 upon movement of the movable contact 17 is smaller than the stroke of contact 17.

Base member 2 provides a connection between a reservoir (not shown) constituting a source of arc extinguishing fluid under pressure and the inlet portion 26 of the arcing chamber 18 for the purpose of directing a blast of arc extinguishing fluid under pressure between the arcing contacts and through the arcing chamber. The arc extinguishing fluid under pressure may be an inert gas such as nitrogen, but it will be assumed herein that the fluid is air under pressure of the order of 200 or more pounds per square inch supplied to the reservoir by a suitable compressor (not shown).

Fig. 2 illustrates more clearly one of the interconnecting conductors 33 and particularly shows the relative position of a pair of ears 41 to the associated conductor 33.

In operation, the circuit breaker being closed as indicated in Fig. 1, current flows through a stationary terminal element (not shown), base member 2, stationary contact 16, movable contact 17, sleeve 23 of piston 24, conductors 33, conductive annular member 9, and stationary terminal element 34. Opening of the circuit breaker is initiated by applying a blast of air under pressure through base member 2 and into insulating tube 13 and the inlet chamber 26. Air pressure is thereby applied to the annular surface of movable contact 17 of piston 24. Piston 24 accordingly lifts contact 17 against the action of the dual purpose springs 39. An arc is thereby drawn between contacts 16 and 17 and at the same time an air blast is established from the inlet chamber 26 through orifice 22, outlet chamber 27, and exhaust outlet 29. Movable contact 17 ultimately reaches the end of its predetermined movement upon infringement of the annular projection of sleeve 23 against flange 25. The gap formed between the arcing contacts 16

and 17 is then of such a value as to provide the most efficient arc extinguishing action of the air blast therethrough.

The air blast causes one root of the arc to move from its initial position on the annular surface of movable contact 17 surrounding orifice 22 to the inner edge of orifice 22. The root of the arc on the stationary contact 16 moves from the point of arc initiation radially and in a downstream direction until it reaches the downstream end of arcing tip 19. The arc also gradually lengthens as its roots are displaced and sweeps through orifice 22 and through a series of positions until one portion of the extended arc loop contacts the auxiliary electrode 31 positioned within the arcing chamber 18. The arc then extends between arcing tip 19 and electrode 31 and is readily extinguished by the air blast. After the arc is extinguished the pressure of the air blast is reduced and the dual purpose springs 39 move piston 24 back to its original position and contacts 16 and 17 reengage for normal operation.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. In a switching device, the combination of a pair of stationary terminal elements, a stationary contact electrically connected to one of said terminal elements, a movable contact adapted to cooperate with said stationary contact and to reciprocate between a pair of extreme positions, a substantially rigid lever resting upon and conductively interconnecting said movable contact and the other of said terminal elements, and dual purpose spring means for establishing contact pressure between said lever and said movable contact and between said lever and said other of said terminal elements and for moving said movable contact from one of said extreme positions to the other of said extreme positions.

2. A circuit interrupter comprising a stationary contact, a movable contact cooperating therewith and defining a first supporting surface, a pneumatic motor for separating said movable contact from said stationary contact, said motor comprising a piston forming an integral part of said movable contact, means for extinguishing the arc formed between said contacts upon separation thereof, a conducting lever in engagement at one end thereof with and supported by said first supporting surface, a stationary conducting element defining a second supporting surface for the other end of said lever, and common spring means for resetting said piston from the contact open position to the contact closed position thereof and for exerting contact pressure between said lever and said supporting surfaces.

3. A circuit interrupter comprising a stationary contact, a movable contact cooperating therewith and defining a first supporting surface, a pneumatic motor for separating said movable contact from said stationary contact, said motor comprising a piston forming an integral part of said movable contact, means for extinguishing the arc formed between said contacts upon separation thereof, a conducting lever in engagement at one end thereof with and supported by said first supporting surface, a stationary conducting element defining a second supporting surface for the other

end of said conducting lever, a pair of ears on said stationary element adjacent said second supporting surface for guiding said lever, and common spring means for resetting said piston from the contact open position to the contact closed position thereof and for exerting contact pressure between said lever and said supporting surfaces.

4. In a switching device, the combination of a pair of stationary terminal elements, a stationary contact associated with one of said terminal elements, a cooperating movable contact in coaxial relation with said stationary contact, contact separating means for moving said movable contact in the direction of the common axis of said contacts, a plurality of conductive rocking levers arranged substantially radially with respect to said common axis for interconnecting said movable contact and the other of said terminal elements, supporting means integral with said movable contact grooved to receive one end of said rocking levers and adapted to permit wiping movement thereon of said rocking levers, means integral with said other terminal element defining a supporting surface for the other ends of said rocking levers, a plurality of stationary supports for helical springs, and a plurality of helical springs each resting with one end thereof on one of said supports and with the other end thereof on one of said rocking levers.

5. In a switching device, the combination of a pair of stationary terminal elements, a stationary contact conductively connected to one of said terminal elements, a movable contact adapted to cooperate with said stationary contact, contact separating means, a plurality of rocking levers for conductively interconnecting said movable contact and the other of said terminal elements, means integral with said movable contact grooved to receive and to support one end of said rocking levers and adapted to permit a wiping movement thereon, means integral with said other terminal defining a supporting surface for the other ends of said rocking levers, and spring means acting upon said rocking levers to produce a wiping action between said rocking levers and surfaces contacting therewith upon movement thereof and to reengage said contacts upon separation thereof.

6. In a switching device, the combination of a pair of stationary terminal elements, a stationary contact conductively connected to one of said terminal elements, a movable contact adapted to cooperate with said stationary contact, lever means resting upon and conductively interconnecting said movable contact and the other of said terminal elements, a fluid motor for separating said contacts, said motor comprising a piston forming an integral part of said movable contact, a source of supply of fluid under pressure, means for admitting fluid under pressure from said source to said motor and adjacent said contacts to cause separation of said contacts and extinction of the arc drawn therebetween, and spring means acting upon said lever means to produce a wiping action between said lever and surfaces contacting therewith and to reset said piston from the contact open position to the contact closed position.

7. In a switching device, the combination of a pair of stationary terminal elements, a stationary contact conductively connected to one of said terminal elements, a movable contact adapted to cooperate with said stationary contact, a piston forming an integral part of said movable contact and defining an annular circular groove having a concave cross section around the circumference

of said piston, a stationary element conductively connected to the other of said terminal elements and defining a concave circular groove having an annular supporting surface, said supporting surfaces extending in a radial direction from said annular groove in said piston, a plurality of levers conductively interconnecting said movable contact and the other of said terminal elements, each of said levers having curved ends of which one end of said lever is supported by the annular circular groove of said piston and the other end of said lever is hingedly supported by the supporting surface of said stationary element, a pneumatic means for actuating said piston for separating said contacts and extinguishing the arc drawn therebetween, and a plurality of helical springs arranged generally parallel to the axis of said contacts and each acting upon one of said levers for resetting said piston from the contact open position to the contact closed position.

8. A circuit interrupter comprising a stationary contact, a movable contact cooperating therewith and defining a first supporting surface, a pneumatic motor for separating said movable contact from said stationary contact, said motor comprising a piston forming an integral part of said movable contact, means for extinguishing the arc formed between said contacts upon separation thereof, a conducting lever in engagement at one end thereof with an supported by said first supporting surface, a stationary conducting element defining a second supporting surface for the other end of said lever, and common spring means for resetting said piston from the contact open position to the contact closed position thereof

and for exerting contact pressure between said lever and said supporting surfaces, said spring means having a smaller stroke than the stroke of said movable contact.

- 5 9. In a switching device, the combination of a pair of stationary terminal elements, a stationary contact associated with one of said terminal elements, a reciprocable movable contact adapted to cooperate with said stationary contact, a substantially rigid conductive rocking lever disposed transversely of the directions of movement of said movable contact with one end thereof resting on only said movable contact and with the opposite end thereof on only the other of said terminal elements, a stationary support for a spring means, and a spring means resting with one end thereof upon said support and with the other end thereof acting on said rocking lever substantially in one of said directions of movement for establishing contact pressure between said lever and said other of said terminal elements and for aiding movement of said movable contact in said one of said directions.
